US00D821428S

(12) **United States Design Patent** (10) **Patent No.:** **US D821,428 S**
Bhat et al. (45) **Date of Patent:** **** Jun. 26, 2018**

(54) **DISPLAY SCREEN OR PORTION THEREOF
WITH A GRAPHICAL USER INTERFACE**

(71) Applicant: **Covidien LP**, Mansfield, MA (US)

(72) Inventors: **Shilpa Bhat**, Sunnyvale, CA (US);
Zheng Zhang, Sunnyvale, CA (US);
Baiyang Qiu, Milpitas, CA (US);
Brady Esch, San Jose, CA (US)

(73) Assignee: **Covidien LP**, Mansfield, MA (US)

(**) Term: **15 Years**

(21) Appl. No.: **29/593,446**

(22) Filed: **Feb. 8, 2017**

(57) **CLAIM**

The ornamental design for a display screen or portion thereof with a graphical user interface, as shown and described.

DESCRIPTION

The FIGURE is a front elevation view of a display screen or portion thereof with a graphical user interface showing our new design.

The broken lines shown in the FIGURE illustrate the display screen and portions of the graphical user interface that form no part of the claimed design.

1 Claim, 1 Drawing Sheet
